E. W. SEAHOLM ET AL

STEERING WHEEL

Filed Nov. 15. 1926

Inventor:

Ernest W. Seaholm &
Harry M. Denyes

By *Blackmores, Spencer & Thiel*
Attorneys.

UNITED STATES PATENT OFFICE.

ERNEST W. SEAHOLM AND HARRY M. DENYES, OF DETROIT, MICHIGAN, ASSIGNORS
TO GENERAL MOTORS CORPORATION, OF DETROIT, MICHIGAN, A CORPORATION OF
DELAWARE.

DESIGN FOR A STEERING WHEEL.

Application filed November 15, 1926. Serial No. 19,740. Term of patent 14 years.

To all whom it may concern:

Be it known that we, ERNEST W. SEAHOLM and HARRY M. DENYES, citizens of the United States, and residents of Detroit, county of Wayne, State of Michigan, and of Saginaw, county of Saginaw, State of Michigan, respectively, have invented a new, original, and ornamental Design for a Steering Wheel, of which the following is a specification, ref-

erence being made to the accompanying drawing, forming a part thereof.

The figure shows in perspective our novel design for a steering wheel.

We claim:

The ornamental design for a steering wheel as shown.

ERNEST W. SEAHOLM.
HARRY M. DENYES.
